CASING PERFORATOR

Herman E. Harr, Long Beach, and Harold Colwell, Downey, Calif.

Application November 11, 1935, Serial No. 49,208

2 Claims. (Cl. 164—0.4)

This invention relates to perforators for piercing holes in casing, such as that ordinarily employed in oil wells, which are adapted for actuation with both standard and rotary drilling tools, by the reciprocation of a drilling line, pipe, tubing or the like to which the device is connected in operation.

The perforation of well casing by the forcible projection of a pointed prong therethrough is well known. A principal difficulty of many of such prior art devices is that they provide for only a single perforating element, and no means are included for offsetting the unbalanced effect of the single thrust. As a result, the perforator will tend to tilt, straining the joints and causing friction between distorted reciprocating parts, which prevents efficient operation and restricts the useful life thereof.

A principal object of the present invention is to provide a device adapted to simultaneously perforate a casing at two diametrically opposite points and to thus balance the pressure exerted through the body of the perforator, which will substantially maintain the central disposition thereof relative to the casing, and preserve the most effective angle of thrust of the perforating members with the casing wall during operation of the tool.

Another object is to provide a device embodying perforating elements of a sufficient length to perforate the walls of several concentric tubings or casings in which the device may be operated, said perforating elements being curved to follow the line of thrust of their points and prevent dissipation of pressure exerted thereon by excessive friction of the shanks of the elements in the perforated holes.

Still another object is the provision of a device embodying durability of construction and operation, ease of assembly, surety of action, and capable of most efficiently utilizing the force of the downward thrust on the reciprocating head of my invention.

Other objects and corresponding advantages will be apparent from an examination of the following description and the accompanying drawing which shows one embodiment of our said invention, in which—

Fig. 1 is a longitudinal view in section and elevation of my invention in elongated position with the perforating members withdrawn into the body;

Fig. 2 is a longitudinal view in section and elevation taken at right angles to Fig. 1 on line 2—2 thereof;

Figs. 3, 4, 5, and 6 are transverse sections on correspondingly-numbered lines of Fig. 1;

Fig. 7 is an elevation illustrating in dotted lines the relative position of the inner parts with the perforating members extended.

Referring more particularly to the drawing, the numerals of which refer to similar parts throughout the several views, 10 designates the upper head of my invention which may be secured in rotary drilled wells by means of a pin 11 to a drill pipe or, in wells drilled by the standard method, to a wire line, by means of sinker bars and jars, which will be obvious to those of skill in this art. Opposite sides of a lower portion of the head are cut away to provide a flat 15 mandrel 12 for its sliding reciprocation within the body 13 of the device, hereinafter described in detail.

The body 13 is provided on its lower end with a pin 14 for attachment to a tubing section, (not shown) by means of coupling 15, on which is mounted downdrive spear mechanism for releasably supporting the body of the perforator against the downward movement, and permitting the relative reciprocation of the head 10 and associated parts therewith. The spear mechanism, being well known in the art, and not forming any part of the present invention, is not illustrated or further described.

The body 13 is preferably constructed in two longitudinal sections 16 and 17 to facilitate assembly, each comprising a half circular lower portion 18 so as to form a round tool when secured to its counterpart by the coupling 15 into which the assembled body is threaded as above noted.

The upper inside portion of both sections are cut away to form faces 19 between which mandrel 12 is adapted to slide. The mandrel is prevented from being withdrawn from the body by oppositely-disposed hooks 20 and 21 integrally formed with the upper ends of sections 16 and 17, having flat sides perpendicular to the plane of faces 19. A slot 22 is formed in head 10 into which the hooks 20 and 21 extend from opposite sides when the lower body is assembled on mandrel 12. The lower limit of slot 22 adjacent mandrel 12 is curved to correspond with the contour of the hooks on which the body of the perforator is suspended during positioning of 50 the spear mechanism.

A stud 23 in the center of the flat side of hooks 20 is provided to extend into a correspondingly shaped hole 24 in the other hook 21, which prevents separation of the hooks or of the sections 55

16 and 17 when in position between the walls of slot 22. In assembling the body sections 16 and 17, one of the hooks is extended through slot 22 so as to protrude outwardly from the other side of the head. The other hook is then placed against the first in operative relationship, with stud 23 engaged in hole 24. The oppositely-extending hooks are then moved into vertical alignment with slot 22, which endless body sections 16 and 17 to assume parallel positions on opposite sides of the body and their relative contact at their lower ends for attachment of coupling 15. When the coupling has been threaded over the lower end of the body the hooks thereof are maintained in slot 22 against lateral displacement by stud 23 and the walls of slot 22.

Perforating members hereinafter described in detail are connected to head 10 by means of connecting arms 25 pivoted to opposite sides of mandrel 12 in a bearing 26 provided therefor. Bearing 26 comprises a circular disk 27 machined in the lower end of the mandrel and having a hole 28 through its center. Downwardly-directed semi-circular shoulders 29 overhang the disk 27 on each side, which the curved ends of connecting arms 25 are adapted to contact to receive the brunt of the downward thrust of head 10. A pin 30 formed adjacent the ends of the arms 25 engages in hole 28 and is reinforced at its upper periphery to withstand the force necessarily exerted in extracting and returning the perforating members from the punctured casing into the perforator body.

The connecting arms 25 are curved to slidably fit in the upper portion of a guide channel 31 provided on the inside of each section, which channels extend to opposite sides of the assembled body. The upper portion of each channel is enlarged and forms a circular shoulder 32 at the lower end of the enlargement against which the connecting arms may abut to limit the downward movement of the upper head. Distribution of the strain of the abutment of upper head and associated elements with the lower body is accomplished by proportioning the device to permit contact of the hooks 20 and 21 with the upper end of slot 22 in head 10 simultaneously with the engagement of connecting arms 25 with the respective shoulders 28 in channels 31.

At the end of each connecting arm 25 a bearing 33 is provided comprising a laterally-extending pin 34. On each of pins 34 a perforating member 35 is pivotally suspended. Each member re-

ceives its downward thrust, from a shoulder 36 formed in the lower end of arms 25 conforming to the shape of the round end of the members 35.

The perforating members adaptable for use in the present embodiment are rectangular in cross-section, with the bezel of the point entirely on the upper end. It should be remembered, however, that the perforating members may be of any shape and associated parts altered to conform therewith.

To most effectively utilize the downward pressure on the reciprocating head, the perforating members should strike the casing at right angles, which may be accomplished by varying in specific embodiments, the curve of arms 25 and perforating members, relative to the length of their thrust to the casing wall. The direction of pressure on the perforating members may be accordingly changed, for maximum efficiency, to comply with the curve of arms 25 and the perforators 35 by the positioning of pins 34 on the perforating members.

It will be obvious to those of skill in this art that changes may be made in the relative size, proportion, number, and position of the various parts hereof, without departing from the spirit of our invention.

Having described our invention, we claim:

1. In a casing perforator, a bifurcated body, a reciprocating head slidably extending between the bifurcations of said body, having a slot longitudinally disposed therethrough, hooks secured to the end of the bifurcations extending from opposite sides into the slot in said head so as to abut against the upper limit of the slot, or suspend the body on the lower limit thereof at respective ends of the reciprocating stroke of said head, and perforating members connected to said head.

2. In a casing perforator, a reciprocating head having a longitudinal slot therein, a body comprising two longitudinal sections, each section of which body having a hook at its upper end adapted to extend into said slot to engage the lower end thereof upon elevation of said head, a connecting arm pivotally attached to the lower end of said head, a perforating member pivoted to the lower end of said connecting arm, and means in said body to guide said perforating member laterally relative thereto.
